UNITED STATES PATENT OFFICE.

JOHN VELCIO, OF YOUNGSTOWN, OHIO.

LIGHTING-FIXTURE SUPPORT.

Application filed February 21, 1921. Serial No. 446,801.

To all whom it may concern:

Be it known that JOHN VELCIO, citizen of the United States of America, residing at Youngstown, in the county of Mahoning 5 and State of Ohio, has invented certain new and useful Improvements in Lighting-Fixture Supports, of which the following is a specification.

This invention relates to electric lighting 10 fixture supports. The principal object is to provide a support that will conceal the electric wire.

Another object is to provide a support 15 that will be flexible, in that each section of the support is so joined so as to allow of universal movement.

Another object is to provide a support, neat in design, and which may be built up to any length desired.

20 The drawing illustrates a preferred embodiment of the invention. However, it is to be understood that in adapting the same to meeting different conditions, various changes in the form, and minor details of 25 construction, may be resorted to without departing from the nature of the invention as claimed and set forth in the drawings:

Figure 1 is a side elevation of the support.

30 Figure 2 is a perspective view of a snap ring.

Figure 3 is detail view showing the two halves of the section.

35 Figure 4 is a detail view showing means of connecting support to fixture.

Figure 5 is a side elevation showing the interfitting relation between two adjacent link members.

40 Corresponding and like parts are referred to in the following description and indicated in the several views of the drawing by like reference characters.

45 By referring to Figure 1 it will be seen I have provided a ceiling plate 1 which is secured in any ordinary way to the ceiling. Into this plate I have provided an attaching member 2 provided with a plurality of attachment ends 3. Into these attachment ends 3 are secured the upper end members 50 4 of the fixture supports 5.

At the lower end of the fixture supports 5, I have shown a bowl 6 attached thereto. It is understood that any form of fixture may be used as desired.

55 By referring to Figure 4 it will be seen that I have provided a bolt 7 which passes

through the fixture 8 and which secures an eye member 9. To this eye member 9 is secured the lower end section 10 which is provided with a channel opening 11 for 60 the purpose of allowing the electric wire to be connected to the electric fixtures and lights within the bowl 6.

By referring to Figure 3 it will be seen that I have shown the two half sections 12 which have ball shaped ends 13 and 14. The ball shaped ends 13 fit over the lower end section 10 when the snap ring 15 is placed over the end 14 and snapped into the circular groove 16, thereby holding the 70 two halves securely in position around the lower end section 10. The fixture supports 5 are now built up in a similar manner with the exception that the two half sections 12 are placed so that the ball shaped ends 13 75 fit over the ball shaped ends 14. The length of the fixture supports 5 may be built up in this manner until the desired length has been secured. It will be seen by referring to Figure 3 that when this is done the fixture supports 5 are provided with an internal channel 17 for carrying the electric wire.

What I claim is:

1. In a device of the class described, two 85 hollow half sections formed with a ball-shaped portion at each end one ball end being smaller than the other ball end in order that the smaller ball end formed by placing the said two half sections together will 90 loosely fit within opening within larger ball end so as to form a universal joint, a circular recess formed on the exterior of said two half sections, a snap ring formed to snap into said circular recess, substantially 95 as described for the purpose set forth.

2. In a device of the class described, two 100 hollow half sections formed with a ball-shaped portion at each end one ball end being smaller than the other ball end in order that the smaller ball end formed by placing the said two half sections together will 105 loosely fit within opening within larger ball end so as to form a universal joint, means for holding said hollow half sections in desired relation to each other.

In testimony whereof I affix my signature.

JOHN VELCIO.
